ABSTRACT

An electron gun structure having a main focusing lens including a unipotential electron lens and a bipotential electron lens, the unipotential and bipotential electron lenses serving as a single main electron lens having a larger effective aperture thereby greatly reducing aberration.

FIG. 1

FIG. 2

FIG. 3

FIG. 4

FIG. 5

ELECTRON GUN STRUCTURE WITH UNIPOTENTIAL AND BIPOTENTIAL LENS

The present invention relates to electron gun structures, and more particularly to an electron gun structure having an electrode system capable of lens action for use in a cathode-ray tube.

As the electrode system capable of lens action for use in a cathode-ray tube, there have heretofore been two types; the unipotential type and the bipotential type. In case of the unipotential type of electrode system, three focusing electrodes are used which are arranged on a common axis in order to form a main focusing lens assembly, two of the electrodes on both sides have applied thereto a common high voltage of, e.g., approximately 25kV, and the other electrode receives a voltage close to ground potential.

In contrast, in case of the bipotential type electrode system, two focusing electrodes are employed which are arranged on a common axis in order to form a main focusing lens assembly, one of the electrodes has applied thereto a high voltage of approximately 25kV, and the other receives a medium voltage of 3 to 6 kV.

These types of electrode system for an electron gun structure has the focusing electrodes arranged so as to constitute a single main electron lens, with the result that a cathode image is focused on the screen by the single main electron lens. In a cathode-ray tube, however, the aperture of the electron gun is restricted by the inside diameter of the neck portion in which the electron gun is received. The aperture of the main electron lens formed is accordingly subject to restriction, and the reduction of aberration is limited. This leads to serious problems especially in the three electron-gun type cathode-ray tube which accommodates three electron guns in the neck portion.

The present invention intends to solve such problems, and has its object in providing an electron gun structure which makes very small the aberration in the main electron lens without increasing the aperture of the electron gun, whereby an electron beam emanating from the electron gun is satisfactorily focused onto the screen.

According to the present invention, there is provided an electron gun structure having a plurality of electrodes for focusing an electron beam on a screen, the improvement comprising a main focusing lens assembly comprising a first electrode means forming a unipotential electron lens and a second electrode means forming a bipotential electron lens.

In the accompanying drawings:

FIG. 1 is a diagram for explaining the basic construction of a main focusing lens system for use in an electron gun structure according to the present invention; and

FIGS. 2 to 5 are schematic views of an electrode arrangement each showing an embodiment of the electron gun structure according to the present invention.

FIG. 1 shows the basic construction of the main focusing lens system used in the electron gun structure according to the present invention. Referring to the figure, the main focusing lens system L_m is composed of two electron lenses L_1 and L_2 . The electron lenses L_1 and L_2 are respectively constituted of a unipotential type electron lens L_u (or a bipotential type electron

lens L_b) and the bipotential electron lens (or the unipotential electron lens). The electron lenses L_1 and L_2 are adapted to form a main electron lens L_m , which is larger in effective aperture. l_1 to l_8 represent loci of electron beams.

When the main electron lens system L_m is constructed of the two electron lenses L_1 and L_2 in this way, the effective aperture of the main electron lens may be made large, and hence, the aberration may be sharply decreased over the prior art. Since the two electron lenses L_1 and L_2 consist, as described above, of the combination between the unipotential type electron lens L_u and the bipotential type electron lens L_b , the main electron lens system L_m may reduce focal variations by means of the unipotential type electron lens L_u with respect to fluctuations in voltage, and it may also reduce an increased beam current by means of the unipotential type electron lens L_u with respect to blooming. Furthermore, owing to the use of the bipotential type electron lens L_b , a fine beam is easily obtained.

FIG. 2 illustrates an embodiment of the electron gun structure according to the present invention, and specifically shows only an electrode system forming the main electron lens system L_m and the way of supplying potentials thereto. Referring to the figure, the main electron lens system L_m is composed of an electrode system consisting of four electrodes, the first to fourth electrodes P_1 to P_4 arranged on a common axis, the first electrode P_1 is arranged so as to be closest to the stem of the cathode-ray tube, and the fourth electrode P_4 is arranged so as to be closest to the face panel of the cathode-ray tube. The electrode system has voltages supplied such that the first electrode P_1 and the third one P_3 are connected in common to apply a high potential from a high potential source E_a to them, while the second electrode P_2 and the fourth one P_4 are connected in common to apply a medium potential from a medium potential source E_b to them, and thereby, a main focusing lens assembly is constructed. In the main focusing lens assembly thus constructed, the first to third electrodes P_1 to P_3 form the unipotential type electron lens L_u , and the third and fourth electrodes P_3 and P_4 form the bipotential type electron lens L_b . As has been explained with reference to FIG. 1, the lenses L_u and L_b form the apparently single main electron lens L_m , of a larger effective aperture.

FIGS. 3 to 5 illustrate further embodiments of the electron gun structure according to the present invention, each specifically showing only the electrode system forming the main electron lens system L_m and the manner of supplying potentials thereto as in FIG. 2.

Referring first to FIG. 3, among the four, first to fourth electrodes P_1 to P_4 arranged on a common axis, the first and third electrodes P_1 and P_3 are in common connected to apply a high potential from a high potential source E_a thereto, while the second and fourth electrodes P_2 and P_4 are respectively applied with different medium potentials from medium potential sources E_{b1} and E_{b2} . Thus, the main focusing lens assembly is constructed. In the assembly, as in the foregoing case of FIG. 2, the first to third electrodes P_1 to P_3 form the unipotential type electron lens L_u , while the third and fourth electrodes P_3 and P_4 form the bipotential type electron lens L_b .

In FIG. 4, among the four, first to fourth electrodes P_1 to P_4 arranged on a common axis, the first and third

ones P_1 and P_3 are connected in common to supply a medium potential from a medium potential source E_b thereto, while the second and fourth ones P_2 and P_4 are connected in common to supply a high potential from a high potential source E_a thereto. Thus, the main focusing lens assembly is constructed. In the assembly, opposite to the foregoing cases, the first and second electrodes P_1 and P_2 form the bipotential type electron lens L_b , while the second to fourth ones P_2 to P_4 form the unipotential type electron lens L_u .

Further, according to the embodiment of FIG. 5, among the four, first to fourth electrodes P_1 to P_4 arranged on a common axis, the second and fourth ones P_2 and P_4 are connected in common to supply a high potential from a high potential source E_a thereto, while the first and third ones P_1 and P_3 are respectively supplied with different medium potentials from medium potential sources E_{b1} and E_{b2} . Thus, the main focusing lens assembly is constructed. In the assembly, as in FIG. 4, the first and second electrodes P_1 and P_2 form the bipotential type electron lens L_b , while the second to fourth ones P_2 to P_4 form the unipotential type electron lens L_u .

As described above, the use of the electron gun structure according to the present invention provides a fine beam electron flow at small aberration, and accomplishes a very high resolution.

What we claim is:

1. In an electron gun structure having a plurality of electrodes for focusing an electron beam on a screen, the improvement comprising a main focusing lens assembly comprising first electrode means for forming a unipotential electron lens and second electrode means for forming a bipotential electron lens.

2. The electron gun structure as defined in claim 1, wherein said first electrode means includes first, second and third electrodes and said second electrode means includes said third electrode and a fourth electrode, said first, second, third and fourth electrodes

being arranged on a common axis in order, said first and third electrodes being electrically connected to each other and supplied with a common high potential and each of said second and fourth electrodes being supplied with a potential lower than that of said first and third electrodes.

3. The electron gun structure as defined in claim 2, wherein said second and fourth electrodes are electrically connected to each other and are supplied with a common potential.

4. The electron gun structure as defined in claim 2, wherein said second and fourth electrodes are supplied with individual potentials different from each other.

5. The electron gun structure as defined in claim 1, wherein said first electrode means includes second, third and fourth electrodes and said second electrode means includes a first electrode and said second electrode, said first, second, third and fourth electrodes being arranged on a common axis in order, said second and fourth electrodes being electrically connected to each other and supplied with a common high potential and each of said first and third electrodes being supplied with a potential lower than that of said second and fourth electrodes.

6. The electron gun structure as defined in claim 5, wherein said first and third electrodes are electrically connected to each other and are supplied with a common potential.

7. The electron gun structure as defined in claim 5, wherein said first and third electrodes are supplied with individual potentials different from each other.

8. The electron gun structure as defined in claim 2, wherein said third and fourth electrodes are of substantially equal diameter.

9. The electron gun structure as defined in claim 5, wherein said first and second electrodes are of substantially equal diameter.
